EXPANSION JOINT FOR PAVEMENTS AND
THE LIKEJames O. Ridgely, Sykesville, Md., assignor to
C. Dudley Shreve, Washington, D. C.

Application April 13, 1937, Serial No. 136,649

12 Claims. (Cl. 94—18)

Generically this invention relates to expansion joints, but it more particularly is directed to the type adapted for concrete roads and the like.

In roads constructed from concrete, expansion and contraction of the material under temperature changes tends to create cracks and fissures not only marring the roadway surface but causing rapid deterioration, and to prevent such consequence, such roads are usually constructed in 5 a plurality of sections spaced from each other to permit longitudinal expansion of the sections, and in order to maintain the contiguous edges of the sections intact and prevent extraneous matter filling the intervening spaces and preventing such expansion it has been found necessary 10 to place an expansion joint in the respective spaces; therefore, one of the principal objects of this invention is the provision of a joint comprising relatively movable parts and which while 15 filling the space between the adjacent concrete sections, permits relative movement of the sections, by reason of temperature variations, without damage to the joint or to the sections.

One of the principal objects of this invention 20 is the provision of an expansion joint of this character connecting the ends of adjacent concrete sections, comprising relatively movable parts initially interlocked to form a unitary structure designed to prevent relative movement and mis- 25 alignment of such parts during handling and installation of the joint.

Another important object of this invention is 30 the provision of an expansion joint comprising relatively movable parts forming an upstanding portion filled with an elastic substance and corresponding to the space between the adjacent concrete sections, said parts being initially connected so that the joint may be installed as a 35 unitary structure, and disalignment of parts during construction of the roadway prevented.

A still further object of this invention is the 40 provision of an expansion joint comprising movable parts and means intermediate the parts substantially corresponding to the space between the 45 concrete section adapted to prevent infiltration of water to said sections and carrying an elastic material, and cap means uniting said movable sections into a unitary structure and covering said resilient material during construction of the 50 roadway, said cap being removable to permit the parts to relatively move with the respective concrete sections on opposite sides of said elastic material upon completion of the roadway.

A further important object of this invention 55 is the provision of a tight water resistant ex-

pansion joint reducing to a minimum infiltration of surface water and adapted to carry off the water without displacement of the sub-grade immediately under or adjacent to the joint, comprising rigid metal holders adapted to effect accurate spacing and alignment of the dowel bars and to insure their being held in a plane parallel to the surface grade or sub-grade profile during the laying of the concrete and which is accomplished without retarding or counter-acting the 10 subsequent movement of the concrete sections by reason of temperature changes.

With these and other objects in view, which will become apparent as the description proceeds, the invention resides in the construction, combination and arrangement of parts, hereinafter more fully described and claimed, and illustrated in the accompanying drawing, in which like characters of reference indicate like parts throughout the several figures, of which:

Fig. 1 is a top plan view showing the joint positioned prior to laying of the concrete;

Fig. 2 is a transverse section taken on the line 2—2 of Fig. 1 showing the device partially embedded in the concrete; and

Fig. 3 is a similar view to Fig. 2 showing the roadway completed and the cap removed and showing the dowel pin cap in section.

The expansion joint structures with which I am familiar, heretofore in use in connection with concrete road construction, have proven deficient in many respects, such as extending from the surface partially through the concrete, others extending completely through to the road bed or base, and while in some instances having parts connected through the joint separating the concrete road sections, such parts have a tendency to become disaligned during laying of the concrete, thereby preventing their proper functioning and causing disintegration of the concrete adjacent to said joint by expansion and contraction caused by temperature changes and permitting further deterioration by the infiltration of surface water, and it was to overcome such deficiencies and to provide an expansion joint structure carrying an elastic material adapted to fill the space between the concrete sections and initially connected as a unitary structure, such rigid connection of the metal plates or holders insuring the dowel bars being held in a plane parallel to the surface grade and in true alignment with their movable connections during laying of the concrete, and upon substantial completion of which, the initial rigid connection is removed leaving the movable sections of the joint

free to move with the relative expansive movement of the concrete in which they are embedded, and, whereby, crumbling, cracking, and consequent deterioration of such concrete portions is prevented, that I designed the expansion joint structure forming the subject matter of this invention.

In the illustrated embodiment characterizing this invention there is shown an expansion joint 10 A and concrete road sections B and C.

The joint A comprises a pair of metallic base plates 1 and 2. Said plates are formed at one end with vertical members 3 and 4, respectively, and which are of a height substantially corresponding to the thickness of the roadway or concrete sections B and C. A metallic trough-like element 5 rectangular in configuration and open at its top and ends, in the present instance, is constructed from bronze material but which may be constructed from any suitable material, is adapted to be positioned intermediate the members 3 and 4 and corresponding in height to said members. One side of said member 5 has its free edge folded upon itself to form an apron-like hook element 6 adapted to engage over the upper edge of member 3, so that the trough element will be connected to and carried by said member. Said trough corresponds in length to that of said joint structure, as will be understood.

30 Suitably connected to base plate 1 by welding, soldering or otherwise are a plurality of spaced dowel rods or bars 7. Each of said dowel bars extends vertically to a point 8 substantially midway of the height of sections 3 and 4 and then horizontally through apertures 9 in members 3 and 4, and 10 in trough 5, and through aperture 11 formed in the upper end of vertical standard 12 struck up from base plate 2 or attached to said base plate by welding, soldering, or in any suitable manner, and mounted on the free end of each of said rods or bars 7 is a tubular cap 13. Dowel rods 7 connected to base plate 1 underlying and embedded in concrete section B project only partially within said caps 13 embedded in concrete section C so that said rods may freely move therein when relative movement of the sections 1 and 2 is effected, as will hereinafter more fully appear.

When assembling the joint A the trough 5, which substantially corresponds in size to that of space D, is adapted to be filled with an elastic substance E such as pitch and the like, and said members 3 and 4 are adapted to contact opposite sides of said trough and are rigidly connected thereto by a cap member 14 inserted over the upper ends of said members 3 and 4 and trough 5. Said cap is locked in place by cotter pins 15 or other suitable fastening elements extending therethrough, whereupon the joint is united into 60 a unitary structure which facilitates handling and positioning on the roadbed prior to laying of the concrete, as will be apparent. It will also be noted that cap 14 not only maintains the parts against displacement during handling and operative positioning of the joint on the roadbed, but protects the elastic material E from extraneous matter during construction of the pavement. It will also be apparent that the filler elastic material E for the space D is carried by the joint A 70, which obviates the use of forms to define such space, and time and labor and subsequent filling of space D with material E, and which facilitates laying of the concrete at such points.

In order to provide a supporting base for the 75 base plates adjacent said space or opening D

and to provide for carrying off water without displacement of the sub-grade immediately under or adjacent to said joint during contraction of said concrete sections and relative movement of the base plate structures, a trough-like base member 16 is positioned at the bottom of space D with its longitudinal edges underlying and supporting the respective base plates 1 and 2, and, irrespective of the movements of said base plates by reason of expansion and contraction 10 of concrete sections B and C, it is obvious that the base plates extending under and facing the ends of the concrete sections B and C, with dowel rods or bars 7 embedded in said sections and extending through standards 12 and into tubular caps 13, and connected parts, are not susceptible of displacement or mis-alignment during the laying of the pavement sections and the expanding and subsequent contracting of said sections, and by reason of which, said adjacent ends 15 of the sections will remain intact and crumbling and cracking by reason of such expansion will be prevented.

It will be apparent that owing, to the rigid integral supporting guide structure intermediate 25 and adjacent the free ends of dowel rods 7, to the rigid connection of the movable sections, to the extensive supporting area of the base plates on the roadbed, to said plates being formed with openings 17 through which wooden pins 18 are 30 driven to anchor the plates in operative aligned position to the roadbed, that displacement or misalignment of parts during construction of the pavement is prevented, and which insures proper relative movement of the parts by reason 35 of contraction and expansion of the adjacent concrete sections, whereby damage to the concrete in the vicinity of the joint is prevented, as explained in the preceding paragraph. The wooden pins are used so that the first movement 40 of the plates in expanding or contracting direction will shear them off leaving said plates free to move with the concrete sections to which they are supportingly attached, as will be clear without further discussion. 45

Owing to the prevalence of the concrete sections adjacent the spaces between such sections, and in which are positioned the expansion joints, to crumble, crack and rapidly deteriorate, it is evident that such joints, owing to their limited 50 surface connection with such sections and mis-alignment of parts, preventing the accurate functioning of such parts in true alignment with the longitudinal direction of the expansion and contraction of the concrete sections, have proven 55 unsatisfactory in use, and it was to overcome such disadvantages that I designed the instant expansion joint adapted to seat on the roadbed, having an extensive supporting base plate area not only presenting a facing for the ends of the 60 adjacent sections, obviating the use during the laying of the concrete of forms for defining the space between the sections, adapted to be filled with an elastic substance, but extending a substantial distance under the respective sections 65 and constituting movable end reinforcing carriage supporting elements, and means supported by and connecting said movable supporting elements, the path of movement of said connecting parts being in true alignment with the direction 70 of movement in expansion and contraction of said concrete sections so as to prevent deterioration of said sections in the vicinity of the joints by relative movement of the sections due to temperature changes. 75

It will be observed from the above description that I have designed an expansion joint adapted to occupy the space between the adjacent ends of the concrete paving sections and to elastically interconnect said sections, comprising relatively movable parts temporarily connected into a unitary structure and including the elastic substance with which said space is usually filled subsequent to the laying of the concrete sections, so that said joint may be positioned on the roadbed to which it is temporarily anchored to maintain the joint in true position during the construction of the contiguous paving sections, and at the time such construction is substantially completed, said temporary connection and elastic substance protective means is removed, whereupon said concrete supporting and reinforcing elements are free to relatively move with their concrete sections, and owing to the elastic substance carrying trough element and the underlying base drain member, the infiltration of water and weakening of the underlying sub-grade in the vicinity of said joint by the entrance of surface water is prevented.

From the above it is apparent that I have designed an expansible joint for connecting adjacent paving sections, including an elastic spacing material, temporarily connected as a unitary structure to facilitate handling and positioning on a prepared roadbed, the connecting means being removable upon substantial completion of construction of the paving sections, said device being simple in construction, comparatively light in weight, manufacturable at a reasonable cost, and efficient for the purposes intended.

Although in practice I have found that the form of my invention illustrated in the accompanying drawing and referred to in the above description as the preferred embodiment, is the most efficient and practical, yet realizing the conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims.

I claim:

1. An expansible joint for concrete roads, or the like, comprising complementary joint sections, each section including a horizontal and a vertical portion, the vertically disposed portions of the respective sections being arranged in parallel and laterally spaced relation, a horizontally disposed dowel rod extending through said vertical portions and relatively moveable with respect to one of said vertical portions, one end of the dowel rod being extended downwardly and anchored at its free end to the horizontal portion of one section.

2. An expansible joint for concrete roads or the like, comprising complementary joint sections, each section including a horizontal and vertical portion, the vertically disposed portions of the respective sections being arranged in parallel and laterally spaced relation, a horizontally disposed dowel rod relatively moveable with respect to one of said vertical portions, one end of the dowel pin extending downwardly and rigidly secured to the horizontal portion of one section, a guide supported by the horizontal portion of the other

section and slidably receiving the free end of the dowel pin.

3. An expansible joint for concrete roads, or the like comprising complementary joint sections, each section including a horizontal and vertical portion, the vertically disposed portions of the respective sections being mounted in parallel laterally spaced relation, a series of horizontally disposed dowel rods relatively moveable with respect to one of the vertical portions, one end of the dowel rods being bent downwardly and anchored to the horizontal portion of one section, a series of guides supported by the other horizontal portion and slideably receiving the free ends of the dowel rods.

4. An expansible joint for concrete roads, or the like comprising complementary metal sections, each section including a horizontal and vertical portion, the vertically disposed portions of the respective sections being arranged in parallel and laterally spaced relation, a metal casing connected to one of the vertical portions and moveable as a unit with said portion, a horizontally disposed dowel rod extending through said vertical portions and casing and relatively moveable with respect to one of the vertical portions, one end of the dowel rod being bent downwardly and having its free end rigidly secured to the horizontal portion of one section.

5. An expansible joint for spaced road paving sections comprising complementary joint sections, each section including a horizontal and vertical portion, the vertically disposed portions of the respective sections being arranged in parallel and laterally spaced relation, a dowel rod bent downwardly and anchored at one end to the horizontal portion of one of the sections and moveable relative to the complementary section, the horizontal portion of said complementary section having a vertical member struck up therefrom adapted to slidably support said rod adjacent to its free end whereby said dowel rod is maintained in the plane of the directional expansible movement of the paving sections.

6. An expansible joint for concrete roads, or the like comprising complementary joint sections, each section including a horizontal and vertical portion, the vertically disposed portions of the respective sections being arranged in parallel and laterally spaced relation, a metal casing being connected to one of the vertical portions and moveable as a unit with said portion, a horizontally disposed dowel rod extending through said vertical portions and casing and relatively moveable with respect to one of the vertical portions, one end of the dowel rod being bent downwardly and rigidly secured to the horizontal portion of one section.

7. An expansible joint for spaced road paving slabs comprising complementary joint sections, the respective joint sections including horizontally disposed base portions and parallelly arranged laterally spaced vertical portions, a casing intermediate said portions, means bonding the casing to one of said sections so as to move as a unit therewith, each of said vertical portions formed with an opening, a guide element carried by one of said sections in alignment with said opening, a dowel rod rigidly anchored to the base portion of one of said sections and extending through said openings and guide and relatively moveable with respect to one of said sections and said guide, whereby said dowel rod is maintained in alignment with said opening, guide and in the

plane of the directional expansible movement of the paving slabs.

8. An expansible joint for concrete roads, or the like comprising complemental joint sections, 5 each section including a horizontal and a vertical portion, the vertically disposed portions of the respective sections being arranged in laterally spaced relation, a dowel rod having a horizontal and a depending portion and relatively moveable 10 with respect to one of said sections, the depending end of the dowel rod being anchored to the horizontal portion of one section.

9. An expansible joint for concrete roads comprising complemental joint sections, said sections 15 including horizontal base portions and parallelly arranged laterally spaced vertical portions, a series of dowel rods horizontally disposed and formed at one end with depending legs anchored to the base portion of one section, and a series 20 of guides carried by the base portion of the remaining section, said guides slideably receiving the free ends of the dowel rods.

10. An expansible joint for concrete roads, or the like comprising complemental joint sections, 25 each section including a horizontal and a vertical portion, the vertically disposed portions of the respective sections being arranged in laterally spaced relation, a horizontally disposed dowel rod formed at one end with a depending leg

anchored at its free end to the horizontal portion of one section and in spaced relation with respect to its vertical portion and a guide carried by the horizontal portion of the other section, said guide slideably receiving the free end of the dowel rod. 5

11. An expansible joint for concrete roads comprising complemental joint sections, said sections including horizontal base portions and parallelly arranged laterally spaced vertical portions, a horizontally disposed dowel rod having one rod 10 bent downwardly and connected to the base portion of one section and a socket element slideably receiving the free end of the dowel rod.

12. An expansible joint for the paving sections of a concrete road and the like comprising laterally spaced members intermediate said sections, 15 said members having oppositely extending horizontal portions, a metal casing containing an elastic substance conforming in dimensions to the space between said spaced members, said casing being connected to and carried by one of said members, dowel rods adapted to extend through said spaced members and casing, said rods having vertical portions rigidly connected 20 at their free ends to one of said horizontal portions, and a removable capping element connecting the upper edges of said members. 25

JAMES O. RIDGELY.
